POWER-OPERATED PIVOTED SHEARS

William F. McPhee, Ringwood, Ill., assignor of
six-tenths to Irvin M. Slepicka, Chicago, Ill.

Application April 25, 1950, Serial No. 157,986

2 Claims. (Cl. 30—228)

1

This invention relates in general to a power cutter and is more particularly described as a portable hydraulic shears which includes a pressure cutter and a hydraulic means for applying pressure to the cutter.

An important object of the invention is to provide a pressure operated clamping jaw type of cutter in which the applied pressure may be sustained or increased and applied as desired.

A further object of the invention is to provide a jaw type of cutter having means for starting the spread of the arms and then applying full pressure at the ends of the arms.

A further object of the invention is to provide a fluid pressure cutter in which the entire pressure is thrown upon a movable cross head attached to the pivotal point of the jaws.

A further object of the invention is to provide the jaws with a circular portion at a distance from the pivot for receiving the direct thrust of fluid pressure applied to the jaws.

A still further object of the invention is to provide a portable cutter of the hydraulic type having a fluid pressure hydraulic pump connected thereto for applying fluid under any desired pressure to the jaws.

Still a further object of the invention is to provide a portable hydraulic power cutter which may be readily moved and transported and made in different sizes for different classes of work.

Other objects of the invention will appear in the specification and will be apparent from the accompanying drawings in which,

Fig. 1 is a view partly in perspective showing a fluid pressure power cutter in accordance with this invention, and a fluid pressure pump for applying pressure to the cutter;

Fig. 2 is a sectional view showing the valve arrangement for the fluid pressure device;

Fig. 3 is a sectional view of the fluid pressure piston in connection with the cutter; and

Fig. 4 is a perspective view of the pivoted ends of the cutter jaws and showing the power applying connections thereto.

Although it is frequently desired to cut rods and cables on the job at a distance from a machine shop, most of such work is laboriously done by means of a hack saw, pipe cutters, and other tools which are neither designed nor intended for the particular purpose.

The present invention provides a powerful hand tool which may be easily carried wherever desired, the cutter jaws being strong and compactly made and having means for applying hydraulic pressure at the ends of the jaws where

2

it is most effective with an accompanying hand operated fluid pressure pump for applying a high operating pressure to the cutter.

Referring now more particularly to the drawings, a pair of jaw members 10 are similar in shape and are adapted to be placed oppositely together to receive a pivoting bolt 12 through aligned holes 14 and each having a rounded surface 16 extending about the axis of the bolt at the inner sides of the members when they are placed together. At the outer ends of the members are jaws 18 which may have extremities 20 for producing a punching and shearing action with each other when they are moved together. Each jaw is formed with a recess 22 which may be used for clamping, securing and shearing action, but preferably a removable jaw member 24 is adapted to be seated in the recess for cooperating with the opposite jaw member when the jaws are moved together. Each jaw member 24 preferably has a shouldered portion 26 for seating it in the recess 22 and a thinner portion 28 overlapping the outer side of the jaw member 10 with a hole 30 therein for receiving a fastening screw 32 which extends into a threaded hole 34 in the jaw member at the edge of the recess 22. At the outer side is a beveled sharp cutting edge 34 with a central recess 36 sharp at the outer edge forming a cutter for small rods, bars and cables inserted therein.

Attached to the outer ends of the pivot bolt 12 is a cross head 40 having opposite perforated sides 42 each extending over one end of the bolt on opposite sides of the members 10 and secured in place by nuts 44 threaded on the ends of the bolt 12. A bolt 46 has a head 48 inserted between the inside of the cross-head 40 and bearing upon the curved surface 16 of the two jaw members. This bolt extends through the cross head and is threaded into a plunger 50 extending radially inward between the jaw members. Surrounding the plunger is a cylinder 52 in which the plunger is movable and at the outer end of the plunger is a washer 54 which makes a fluid tight connection with the inside of the cylinder. At the inner end of the cylinder is a projecting collar 56 secured to or formed integrally with the cylinder having opposite inclined surfaces 58 and having a projection 60 on one or both sides with a threaded perforation for receiving a bolt 62 extending therefrom parallel to the cylinder.

The adjacent inner portion of each jaw member 10 has an inside projection 64 with an inner inclined surface 66 adapted to be engaged by the

inclined surface 58 of the collar when it is moved relatively outward between the jaw members in their collapsed position. Tending to return the jaws to their collapsed position is a spiral spring 59 disposed in the cylinder 52 abutting the closed end of the cylinder at one end of the spring and abutting the inner end of the plunger 50 or the exposed face of the washer 54 attached to the plunger.

Mounted for free sliding motion upon the outside of the cylinder is a collar 68 having a lateral projection 70 on one or opposite sides corresponding to the projection 60 (or projections) of the collar 56. The bolt 62 extends freely through a perforation in the projection 70 and is provided with a nut 72 at the outer end of the bolt to limit the movement of the collars 56 and 68 apart, but to allow them to move relatively together. At opposite sides of the collar 68 are projections 74 having pivot pins 76 extending therethrough for receiving arms 78 pivoted therein, the outer end of each arm being connected by a pivot 80 with a pivoted bolt 82 attached through the outer end of the jaw member 10.

At the outer end of the cylinder 52, a hollow sleeve 84 is inserted and adapted to receive an end fitting 86 of a pressure hose 88 threaded or attached therein.

With this construction, fluid pressure applied to the inside of the cylinder 52 will spread apart the cylinder and the plunger 50. Since the plunger is rigidly attached by means of the cross head to the jaw members with the head 48 of the fastening bolt bearing upon the jaw members, the plunger is held firmly but the cylinder is forced outwardly and if the jaw members have been collapsed or moved tightly together, the collar 56 at the inner end of the cylinder will engage its inclined surfaces 58 with the inclined surfaces 66 of the jaw member projection 64 first moving the jaw members angularly apart.

Since there is a slight lost motion between the collars 56 and 68, the collar 68 is not moved outwardly on the cylinder until the lost motion on the bolts 62 is taken up and the collar 56 bears against the outer or adjacent end of the collar 68. When the cylinder 52 has been moved to this extent, pressure is then applied by the cylinder to the collar 68 forcing the arms 78 outwardly. At this time, the jaws have been moved outwardly so that the pressure against the arms 78 is at a greater angle to the adjacent inner surfaces of the jaw members and is held nearly normal to the ends of the jaw members which is the position where the jaws are actually the closest together.

A suitable pump for applying fluid pressure comprises a short pipe 90 to one end of which the free end of the hose 88 is attached. At the other end of the pipe 90 are fittings 92 connecting it with a cylinder 94 for supplying fluid under pressure to the pipe. At the top of the cylinder is a cap 96 and extending through the cap is a stem 98 of a plunger 100 in the cylinder. At the cylinder end of the pipe is a ball valve 102 having a seat 104 and at the other end of the pipe is a ball valve 106 having a seat 108. The ball valve 102 is held in place by a spring 110 and the ball valve 106 is held in place by a spring 111.

Extending upwardly from the middle of the pipe is a plunger cylinder 112 having a plunger 114 movable therein by means of the stem 116. The stem extends through a fitting 118 at the top of the cylinder 112 where it is connected by a stirrup fitting 120 intermediate the ends of a handle 122. The adjacent end of the handle is 75

connected by a stirrup fitting 124 with an upright post 126 fixed to a base 128 to which the pipe 90 is also attached by means of a strap 130.

At the discharging end of the pipe 90 between the ball 106 and the end of the pipe is a shut off valve comprising a hollow valve mounting 132 connected through the pipe 90 and having a valve 134 engaging a seat 136 at the bottom of the housing 132. The valve is operated by a stem 138 threaded through the valve casing and having a handle 140 for moving the valve into and out of engaging position with the valve seat 136. Extending laterally from the valve casing 132 is a pipe 142 which is connected by means of a fitting 144 into the lower end of the cylinder 94 so that pressure may be admitted to the bottom of the cylinder and the valve may be opened to relieve pressure applied through the valve 106 to the cylinder of the power cutter and to by-pass the pressure and fluid back to the supply cylinder 94. When pressure is applied to operate the power cutter, the valve 134 is closed and the valves 102 and 106 are automatically operated to withdraw fluid from the cylinder 94 upon an up-stroke of the plunger 114 and to apply additional pressure to the power cutter through the valve 106 by the down-stroke of the plunger 114.

With this construction, the power cutter is easily applied so that the jaws are in clamping engagement and in position to cut, grip or clamp an object between the jaws or the jaw members 24 thereof. To release the jaw members 10 for moving the jaws apart, it may be necessary to open the relief and by-pass valve 132 which relieves any pressure upon the cylinder 52 and plunger 50 so that the jaw members 10 may be pressed together moving the collar 56 relatively inward within the projection 64 of the jaw members. This separates the engaging jaw portions so that a rod, cable or plate to be cut or clamped may be inserted between the clamping jaw portions as desired.

Pressure is then applied between the piston 50 and cylinder 52 by operating the handle 122 which causes the collar 56 carried by the cylinder 52 to move outwardly upon the plunger 52 so that the inclined surfaces 58 of the collar engage the adjacent inclined surfaces 66 of the jaw members pressing them angularly apart and partially separating the power applying ends of the jaw members to take up any slack or lost motion between the collar 56 and the collar 68 surrounding the cylinder so that the further application of pressure from the pump tending to separate the plunger 50 and the cylinder 52 will engage the collar 68 and through the arm 78 will apply pressure received by the collar to the extreme ends of the jaw members 10 and held nearly in a straight line at opposite sides of the collar 68 so that the greatest leverage will be applied.

If it is desired to hold the power cutter in a fixed position, clamping an article between the jaws thereof, the fluid pressure may be maintained in the cylinder 52, or it may be increased by operating the handle 122, or it may be decreased either slowly or suddenly by opening the valve 132.

To release the jaw members, the valve 132 must be open to permit a flow of the fluid under pressure through the by-pass 142, whereupon the power applying ends of the jaw members may be moved together, the collar 68 engaging the collar 56 and moving it inwardly until the jaws are released or separated as desired.

This construction may be made in large per-

manently mounted sizes, but it is particularly adapted to be produced in small or portable sizes so that not only the jaws, but also the connected power applying pump may be adapted and included as a portable part of the mechanism.

While I have thus described a preferred embodiment which has been described in some detail, it should be regarded by way of illustration and example rather than a restriction or limitation thereof, as many changes in the construction, combination and arrangement of the parts may be made without departing from the spirit and scope of the invention.

I claim:

1. A power cutter, comprising a pair of jaw members pivoted together adjacent the jaws thereof, a plunger and means for connecting it to the jaw members at the pivot thereof, a cylinder movable upon the plunger having a collar at the inner end with opposite contact surfaces thereon, the jaw members having inner projections adapted to be engaged by the projections of the said collar when the cylinder is moved inwardly to position the collar between the projections on the members and the pivot thereof, means movable on the cylinder engaged by the collar and connected to the outer ends of the members remote from the jaws thereof to actuate the jaws, means for applying pressure to the cylinder for moving the projections of the collar in engagement with the projections of the members to initially separate the jaw members when the cylinder is moved relative to the plunger and to engage the collar movable on the cylinder for applying pressure to the ends of the jaw members and to the jaws.

2. In a power cutter, a pair of jaw members and a pivot connecting them adjacent to the

jaws, a cross head connected to the pivot, a plunger connected to the cross head, a cylinder movable on the plunger between the power applying ends of the jaw members, the jaw members having projections at their inner edges adjacent but spaced from the pivot thereof, a collar attached to the cylinder having opposite projections to engage those of the jaw members when the cylinder is moved outwardly, a collar movable upon the cylinder, a lost motion connection between the movable collar and the fixed collar to permit the movable collar to approach the fixed collar, arms connecting the movable collar to the power applying ends of the jaw members, and means for applying fluid pressure to the cylinder to initially separate the jaw members by the engagement of the said projections of the collar with the projections of the members and to take up the lost motion connection between the collars and to apply the collar loose on the cylinder to the further separation of the jaw members.
